UNITED STATES PATENT OFFICE.

EMMA B. HANSON, OF NEW ROCHELLE, NEW YORK.

WARDROBE-TRUNK CONSTRUCTION.

Application filed December 3, 1925. Serial No. 72,911.

This invention relates generally to a wardrobe trunk construction.

In the manufacture of wardrobe trunks difficulty has been found in successfully applying the wardrobe feature to trunks of the steamer type. As heretofore constructed trunks, including those of the wardrobe type, have been provided with a hinge joint extending along one of the longer sides so that the trunk, as a whole, had to be turned up on one end to thereby bring the wardrobe part into a vertical or upright position. The requirement of turning the entire trunk to an upright position is particularly objectionable with trunks of the steamer type which, because of the restricted space in staterooms, are placed beneath a berth when not in use, thereby entailing the handling of the trunk whenever it is desired to have access to the contents thereof.

A general object of the present invention is to provide a wardrobe trunk construction which will be free from the objectionable features referred to.

The invention includes a trunk construction in which the cover section is hinged across one end to the body portion and is arranged to provide a wardrobe compartment. With this arrangement it is necessary to lift only the cover portion of the trunk to erect position to provide a wardrobe structure and, because of the light weight of the contents, this can readily be accomplished.

Other features of the invention will be hereinafter referred to.

In the drawings, in which a preferred embodiment of the invention has been selected for illustration,

Figure 1 is a view in side elevation of a wardrobe trunk embodying the invention and shown in open or functioning condition.

Figure 2 is a view in front elevation of the trunk shown in Figure 1.

Figure 3 is a perspective view of the trunk in closed condition.

Figure 4 is a view similar to Figure 2 showing the compartment portion of a trunk in raised position and the wardrobe portion in lowered position.

Referring to the drawings for a more detailed description of the invention, a trunk is shown of the steamer type which includes a body or compartment portion 10 and a combined cover and wardrobe portion 11. A feature of the invention resides in a piv-

oted or hinged connection of the parts 10 and 11 along one end as at 12 as contrasted with the ordinary trunk construction in which the hinged joint is placed along one of the longer sides of the article.

The cover or wardrobe portion 11 of the trunk has substantially the same depth as the compartment portion 10 and is provided with suitable equipment or accessories for supporting garments placed therein in a suspended condition. For this purpose a series of garments hangers 13 is mounted in the upper portion of the wardrobe section, a hinged rack member 14 being provided for the support of the hangers.

A removable bar or slat member 15 is preferably provided intermediate the ends of the wardrobe section and located adjacent the open side thereof for the purpose of holding the garments in place within the container section 11.

An additional retaining member in the form of a rod 16 is pivoted at one end to the inner side of the container wall 11 as at 17 and is provided at the other end with a hook member 18 for engagement with an eye member 19 on the opposite wall of the container 11 to function as an additional retaining member to hold garments in place within the cover section 11. The rod 16 may be swung from the holding position shown in dotted lines in Figure 2 of the drawings to a diagonal or inclined position such as is shown in Figure 1 to thereby engage an eye member 20 in the body portion 10 and to serve as a support or brace for the cover section 11 when in raised position.

It will be seen that the provision of a wardrobe section hinged along one end facilitates the raising of the wardrobe section to a vertical or upright position in that only that portion of the trunk which provides the wardrobe section is required to be lifted to the erect position. It will be seen that this eliminates the turning of the entire trunk to an upright position such as is called for in wardrobe trunk constructions heretofore known and used.

The facilitating of the lifting of the wardrobe section of the trunk to raised position is particularly applicable for use in the restricted space provided in staterooms on board ship in which the trunk when not in use normally occupies a position beneath a berth. The drawing of the trunk from beneath the berth and the elevating of the

cover section is not a difficult operation so that the use of a wardrobe trunk of the steamer type is thus provided for in a practical and feasible manner.

5 It will be seen that, if desired, the wardrobe section 11 of the trunk may be used as the base member as in Figure 4 of the drawing, the compartment section 10 being then elevated to the erect position shown whereby 10 access may be had to the individual compartments through the hinged door or closure members 21 pertaining thereto.

15 To facilitate the most effective use of the trunk, a handle member 22 is placed in the middle of the long side of the base section 10 as is shown in Figure 3 of the drawings, this handle being particularly useful in drawing the trunk from a position beneath a berth. A handle member 24 is provided 20 on the end of the body or compartment section 10 remote from the hinged end 12, in addition to which a handle member 23 is provided on the end of the cover member which occupies an elevated position when 25 the cover section 11 is functioning as a wardrobe.

The language and expressions which have

been employed throughout the specification are used as terms of description only and not of limitation, and such terms are intended to include all the equivalents and such modifications as are possible to be employed within the scope of the invention claimed.

What I claim is:—

30 In a trunk of the steamer type, a body section, a cover section, said cover section being hinged across one end to the body section and arranged to serve as a wardrobe compartment, a rod hinged at one end to a 40 side wall of the cover section and adapted to extend across the compartment and be removably attached to the opposite side wall to hold garments in place in the compartment, and said rod being adapted to be 45 swung about its hinged end and attached at the other end to the body section, whereby to serve as a diagonal brace rod, to hold the cover in erect position.

35 Signed at New York, in the county of 50 New York and State of New York, this 30th day of November, 1925.

EMMA B. HANSON.
